UNITED STATES PATENT OFFICE.

FRANK S. FARRAR, OF LYNDON, KANSAS.

SECTIONAL MOLD FOR CONCRETE CONSTRUCTION.

962,560.

Specification of Letters Patent. Patented June 28, 1910.

Application filed September 14, 1908. Serial No. 453,045.

To all whom it may concern:

Be it known that I, FRANK S. FARRAR, a citizen of the United States, residing at Lyndon, in the county of Osage and State of Kansas, have invented certain new and useful Improvements in Sectional Molds for Concrete Construction, of which the following is a specification:

This invention relates to molds for plastic structures, and more particularly to a sectional mold adapted to use for building conical arches and similar structures.

An object of the invention is to provide a support for concrete arches which will be adjustable to vary the radius of an arc without the use of permanent forms.

Another object is to provide retaining portions of a novel and desirable type.

Another object is to provide a form for walls provided with means for quickly adjusting the thickness to be given a wall, and having also novel means for holding the retaining portions in position.

Another object is to provide a retaining means for end walls of arched structures the size of which may be adjustably varied.

Another object is to provide novel means for holding adjacent ends of retaining sections in position.

Another object is to provide novel and desirable means for holding the extremities of mold sides in registry.

Another object is to provide a mold for cylindrical structures, adjustable to vary the diameter of a structure without the necessity of special forms.

Another object is to provide a dome mold for use with cylindrical molds or without them, the dome molds being adjustable to vary the size as desired.

Another object of this invention is to provide a novel and desirable means for holding the sides of a wall mold in an adjustable spaced relation, this means forming also a tie member in the wall when the structure is completed.

Another object is to provide a means for building a wall having an outer layer of fine grain material, backed by coarser material, in order to provide a wall impervious of moisture without involving great expense.

Other objects and advantages will be apparent from the following description, and it will be understood that changes in the specific structure shown and described may be made within the scope of the claims with-

out departing from the spirit of the invention.

In the drawings forming a portion of this specification, and in which like numerals of reference indicate similar parts in the several views, Figure 1 is an end view of the mold showing the arch and wall portions in position, Fig. 2 is a view at right angles to Fig. 1, Fig. 3 is a plan view of a form for an end wall, Fig. 4 is a view of a quarter section of the dome form, Fig. 5 is a detail of one of the links in the arch section, Fig. 6 is a detail edge view of one of the links, Fig. 7 is a detail of the junction of the cross pieces and vertical supports with the base of the arch, Fig. 8 is a cross section of one of the retaining members, Fig. 9 is a view of a wall mold in position and showing a wall gage in position therein, Fig. 10 is a plan view of three forms of tie means for engaging the support portions of wall molds in spaced relation, Fig. 11 is a detail view of a modified form of link for the sectional arch, Fig. 12 is a detail view of a movable diaphragm for use in the mold to embrace materials of different kinds, Fig. 13 is a detail of a means for coengaging the end plates to retain them firmly in operative position, Fig. 14 is a modified device for holding the end plates in coengagement, Fig. 15 is a modified form of end retaining portion suitable for culvert, Fig. 16 is a modified form of means for securing end sections detachably in position, Fig. 17 is a detail side view of a form of link for the outer portion of an arched form, Fig. 18 is a detail of gage for setting the links of the arch.

Referring to the drawings, there is shown a form for molding concrete structures, comprising an arch formed of links 10 pivotally coengaged, the base of the arch being braced by a sectional cross piece 11, and being supported upon upright members 12 detachably engaged therewith, as shown. The uprights 12 comprise spaced rods secured to each other at intervals by means of bolts engaged through the rods and through blocks 13 disposed between the rods 12' to hold them in spaced relation. The supports 12 may be made of any suitable form of metal, and as shown are formed of small L beams arranged with one of the flanges on each in adjacent spaced relation, the remaining flanges extending outwardly. A detachable ground engaging portion is detachably engaged with the upright 12 and comprises a

pointed member 14 having a socket 15 formed in the upper end thereof of angular shape adapted to engage detachably over the end of the upright 12, as shown.

5 The adjacent L flange portions of the members 12' are perforated at their upper ends and adapted to engage with the flange carried by the cross piece 11. The cross piece 11 comprises two small L beams having their inner end portions disposed in overlapped relation, and provided with spaced openings 16 therethrough adapted for adjustable engagement by means of pins 17 engaged therethrough, as shown. Carried 10 by the outer end of one of the beams 11 there is a block 18, said block having an upwardly extending ear 19 having an opening therethrough and a downwardly extending ear disposed therebeneath and having 15 an opening therethrough, the upper ear being adapted for engagement with the links 10 of the arch portion, as shown, and the lower ear being adapted for engagement with the upright 12. The opposite member 20 25 carries at its outer end a similar block having spaced ears 20 on the upper side thereof adapted for engagement with the links 10 and a single ear therebeneath adapted to engagement with the upright 12. 30 The links 10 are each similarly formed, and comprise a solid bar having a longitudinally extending ear 22 at one end thereof, and having spaced ears 23 formed at the opposite end and adapted to engage slidably over the ear 22 of a similar link, the ears 22 and 23 having concentric perforations 24 formed therethrough adapted to receive pins 25, as shown. Projecting inwardly of each link at one end there is a 35 lug 26 having a threaded opening therethrough extending longitudinally of the body portion of the link and having a set screw 27 engaged therein as shown. The opposite end of the link is provided with a 40 lug 28 as shown. The outer faces of the lugs are beveled inwardly to allow pivotal movement of the links with respect to each other when connected by the pin 25, and it will be seen that by means of the set screw 45 50 55 27 the relative movement of the links may be limited, the end of the screw engaging against the adjacent face of the lug 28. Intermediately of the links 10 there is formed an opening 29 for a purpose to be subsequently indicated.

The uprights 12 have spaced registering openings 29' formed through their adjacent flanges, as shown, to receive the ends of tie members 30, the latter being adapted to 60 similarly engage and support adjacent uprights in spaced relation therewith. Tie members 39 are similarly engaged in the openings 29 formed in the links 10, to hold the adjacent arch sections A in spaced relation. Disposed outwardly of the uprights

12, in spaced relation therewith, there are similar uprights held in spaced relation therewith by means of ties 32, comprising strips of sheet metal stamped to present opposite engaging notches 33, the ties being 70 presented in a vertical plane between the rods 12' and then turned laterally to engage the notches with opposite flanges of the rods to hold them against relative lateral movement.

75 The tie members 32 need have but one notch at one end, as shown, and the opposite end may be provided with a series of notches to allow latitude in the adjustment of the space between the uprights 12. Wall plates 80 34 are disposed inwardly of and against the uprights 12, and comprise blanks of sheet material having their opposite longitudinal edges bent backwardly to stiffen them longitudinally, and having a series of cross ribs 85 36 spaced throughout their length to prevent bending of the plate laterally. The flanges 35 are disposed outwardly, so as to present a smooth face inwardly of the upright 12 to form a mold for a wall. Disposed inwardly 90 of the plates 34 and adjacent to their ends there is an end member or gage 38 comprising two plate members 38' formed of sheet material coengaged slidably to vary the width of the gage. One of the plates 38' has 95 formed therethrough a series of laterally extending slots K and the opposite plate 38' carries a series of bolt members L disposed slidably in the slots and having nut members engaged outwardly of the coengaged plate 100 to secure the plates adjustably in lateral relation. The member 38 serves to hold the form plates 34 in position, being placed inwardly of the tie members 32 which serve to prevent it from being forced outwardly by 105 concrete when poured into the mold. It will be seen that a series of arch sections A may be thus constructed, and by means of tie rods 39, engaged in the openings 29 formed in the sections 10 and uprights 12, the sections being secured in adjustable spaced relation. Convex faced form plates 40 are disposed upon the outer face of the arch section 10 beginning at the base of the arch as shown, the lower of the convex plates being disposed closely against the upper of the form plates 34, as shown.

110 There is shown at 42 a disk having a series of peripheral notches 44, the sides of which notches extend inwardly at varying angles 115 with respect to each other and adapted to form a gage for setting the links 10 of the arch section to form arches of a given degree of curvature. In use, the disk is intended to be placed upon the head of the pin 25, and one of the notches 44 disposed centrally over the junction between the end faces of the lugs 26 and 28. The set screw 27 is then operated to bring the adjacent faces of the lugs 26 and 28 to the same relative angle that 120 125 130

the sides of the notch 44 in the disk 42 indicate.

In Fig. 11, there is shown a modified form of connection for the links 10 in which the lug 28 is provided with a single lateral opening therethrough, and the lug 26 is provided with a plurality of similar openings disposed at various distances from the end face of the lug. A small yoke member 45 is used to adjust the angle of the links and comprises a long arm 46 slidably engaged through the opening in the lug 28 and a spaced short arm 47, detachably engageable in one of the openings through the lug 26 and connected with the first arm by a bight portion 47. A head portion 28' is formed on the extremity of the arm 46 to hold it against removal from the lug 28, as shown. It will be seen that the yoke 45 may be lifted from engagement with the lug 28, for adjustment in different openings to vary the relative angle of the attached sections 10. There is shown also in Fig. 11 a form of plate 40' adapted to be secured upon the section 10' permanently so that the section and attached plate may be retained in permanent engagement. It will be noted that the plate 40' has the link 10' secured laterally thereon, one longitudinal edge of the plate being bent outwardly to receive the edge of an adjacent plate slidably thereunder. This is suitable for use in small structures though it is probably impracticable for structures of large size. It will be seen that the pin 25' connecting the links 10' extends laterally outwardly and the plates 40' carry pivoted hook members 49 engaged over the adjacent end portion of the pin 25', as shown.

In Fig. 3 there is shown a means for providing a retaining portion for an end wall form under an arch, which comprises removable arcuate plates 50 disposed in concentric series, a central semi-circular portion 51, a wall portion comprising uprights 53 of the same width as the sections 50, and an inner portion 54 of the same width as the portion 51. The inner portions of the sections 50 carry fastening members 55 comprising metal plates secured across their outer end faces and projecting laterally beyond the edge of the plate a distance equal to the width of the sections, the projecting portions being offset outwardly of the remaining portion a distance equal to the thickness of the plate. Spaced tongues 56 having upwardly turned extremities are formed integrally on the edge of the plate 55 adjacent to the end of the attached plate 50 and turned laterally outward as shown. The projecting portion of the plate 50 carries hook members 57 adapted to engage over the flanges 56 carried by an adjacent member 50 when two such members are disposed in operative position, as shown. Plates 55' carrying only

flanges 56 are disposed upon the semi-circular portion 51 for engagement with the hook members 57 of attached portions 50. The adjacent edge portions of the members 51 and 54 carry plates 55 similar to those first described. The adjacent end portions of the outer sections of the end wall, as shown in Fig. 3, and the edge portions of the sections 51 and 54 are held securely in detachably engaged position by means of a clamp member 58, comprising spaced bars 59 having bolts 60 coengaged therethrough and engaged over the adjacent flanges 56 of the various sections, as shown, the bolts 60 being operated to bring the bars into close engagement upon the flanges 56 to hold them securely against removal.

A wall portion similar to that shown in Fig. 3 may be disposed at the end of an arch and slightly inwardly thereof and a second similar wall portion disposed outwardly thereof in proper spaced relation, the outer retaining portion of the side walls, and arch being extended outwardly the distance desired for the thickness of the end walls, and being in contact with the outer end retaining portion. It will thus be seen that an end wall may be constructed integrally with an arch in a very simple manner.

It will be noted that the width of the end wall and the radius of the arch may be varied by the removal or addition of sections 50 and 53 as will be understood. By the removal of the portions 51 and 54 and also the portion 53, if desired, it will be seen that a side retaining wall for a culvert may be formed, and by means of the addition of corner pieces 61 the wall may be built up and given square corners as will be understood. In order to form the inner retaining portion 105 for the retaining wall of the culvert over an arch, a sufficient number of the sections 50 may be disposed over an arch and secured thereon in spaced relation as will be understood, the sections 51 being disposed thereon 110 also, if desired.

In Fig. 15, there is shown a modified form of end retaining portions for culverts which is well adapted to use with small structures, and comprises base side portions 62 having portions of their adjacent ends cut away to form a semi-circular opening 63 and having retaining members 64 disposed thereupon. There is shown in Fig. 14 a detail of the means for securing the outer ends of the members 64 in position which comprises strap members 65 fastened to the upper edges of the members 62 and 64, and T-shaped bars 66 attached to the lower edges of the members 64 and adapted to sliding engagement in the strap 65. The straps 65 are bowed outward at their center in angular form adapted to closely engage with the members 66 as shown. It will be understood, however, that if desired the first de- 130

scribed form of securing means shown in Fig. 16 may be substituted for the form just described.

There is shown in Fig. 4 a dome for use upon upright cylindrical structures which comprises segmental plate members 70 having coengaging members similar to those described for holding the members 50 together and adapted to be disposed upon the 10 inner retaining portion of the cylindrical wall form. It will be understood that the structure of the links and cross pieces may be changed as desired to meet various conditions and to improve the operation of the 15 structure. It will also be understood that the uprights described and other co-operative portions of the structure may be varied within the scope of the claims as may be found advantageous. It will be understood 20 that the arch section A may be extended as desired, and may form a circle, and when an upright cylindrical structure is to be constructed the plates 40 may be disposed upon one end against a cylindrical 25 circular frame comprising the sections 10 and an outer retaining portion disposed in spaced relation therewith after the manner above described. There is shown in Fig. 4 a cylindrical collar member 70' adapted to 30 be disposed centrally upon the dome portion to form a vertical opening through the dome when constructed, for use as a man-hole or otherwise. It will be understood that any suitable form of tie may be substituted 35 for the form illustrated, including rods engaged through suitable openings formed in the uprights and secured by nuts or other suitable means.

Fig. 12 illustrates a form of movable diaphragm adapted to be disposed between the retaining plate of a wall form, and adapted to be drawn upward as concrete is poured into the mold. The diaphragm is intended to form a partition to separate different kinds of material which may be found desirable to incorporate in a wall, to form a structure having different structure on one side from that on the adjacent side. This would be of advantage in forming a wall 45 having a facing of close grain material and a backing of coarser material, it being thus possible to form a water-proof wall of any desired thickness, at relatively slight expense as compared to what it would cost if 50 made entirely of material sufficiently fine and compact to resist the seepage of water. The diaphragm consists of a central plate 80 having a plurality of L-shaped members secured longitudinally thereof to its upper 55 edge and presenting horizontal arms 81 having spaced perforations therethrough. Resilient L-shaped members 82 having opposite arms 83 and 84 extending at an oblique angle, are secured to the arms 81 slidably 60 by means of bolts 84 engaged through longi-

tudinal slots formed in the arms 82 to hold the diaphragm 80 adjustably at any point in the length of the slot. The arms 82 are pendent and directed slightly outward so that when the diaphragm is disposed between the retaining portions of a wall section the arms 83 will engage yieldably with the opposite sides of the form to hold the diaphragm in spaced relation with the sides of the form. It will thus be seen that the 75 diaphragm may be adjusted to any desired distance from either side of a wall form to divide material when poured into the mold and adapted to be drawn upwardly to allow the segregated material to unite. 80

It will be understood that ordinary lumber or other suitable means may be utilized for the wall plates 34, and the end walls if desired. The use of the arcuate plate members is particularly applicable in the construction of cisterns, wells, and man-holes where circular and domed walls are necessary. 85

What is claimed is:

1. A side for a mold comprising a plurality of sections, and means for holding said sections detachably in operative position, said means comprising plates carried at the inner edges of said sections and having laterally projecting flanges, and spaced bar members adapted to coengage with the flanges of adjacent sections and means for clamping said bars adjustably on said flanges. 95

2. In an article of the class described, an arch support comprising a plurality of link members, said link members comprising a body portion longitudinally arcuate, an integral concentrically perforated ear projecting from one end thereof, spaced concentrically perforated ears projecting from the opposite end and adapted for engagement over the single ear of a like member, the end faces of the sections being beveled inwardly from the ears, and means for adjusting the relative angles of coengaged sections. 100

3. In an article of the class described an arch support comprising a plurality of sections, said sections each comprising a cast arcuate body portion, an integral concentrically perforated ear projecting from one end of each section, spaced concentrically perforated ears projecting from the opposite ends, and coengaged pivotally with the single ears of an adjacent section, said sections having lug portions at their ends projecting laterally in the plane of their arc and being beveled inwardly from the ears, and means coengaged between adjacent ends of the sections for adjusting their relative angles. 110

4. In an article of the class described an arch support comprising a plurality of sections, said sections each comprising a cast arcuate body portion, an integral concentrically perforated ear projecting from one end 115 120 125 130

- of each section, spaced concentrically perforated ears projecting from the opposite ends, and coengaged pivotally with the single ears, said sections having lugs at their ends projecting laterally in the plane of their arc and being beveled inwardly from the ears, each of said sections having a transverse perforation at one end outwardly of the ears, a U-shaped member provided with a long 5 and a short arm, the long arm being engaged slidably in said perforation, means for retaining said arm against casual disengagement therefrom, the opposite end of each of the segments being provided with a plurality of transverse perforations variably spaced longitudinally of the section, said U-shaped member being adapted for movement to engage the short arm in said second named openings to secure adjacent sections adjustably at different relative angles.
5. In a device of the class described, a retaining plate for mold sides comprising a blank of sheet material having opposite edge portions bent laterally at right angles to form spacing flanges and having transversely extending ribs formed of L-shaped members secured between the flanges, said plates being adapted to be disposed edge to edge with similar plates to present a continuous smooth 20 inner mold face.
6. The combination with a mold for plastic structures, said mold having spaced wall portions, of a diaphragm member adjustably spaced intermediately of said walls and adapted for vertical sliding movement there- 25 30 35
- between, said diaphragm comprising a partition member, L-shaped members secured thereto and presenting laterally extending arms, and L-shaped members having horizontal portions disposed slidably upon said arms and having pendent portions disposed respectively on opposite sides of the partition portion and a clamping member engaged with the horizontal portion and arms. 40
7. In a mold, the combination with uprights each comprising spaced members, of a tie member comprising a strip of sheet material having longitudinally spaced notches formed in opposite sides, said tie being adapted to be presented between the uprights in a vertical plane, and twisted into a horizontal plane to engage said uprights in the notches for retention of the uprights in fixed spaced relation. 45
8. In a mold of the class described, the combination of a plurality of segmental wall sections adapted to be disposed edge to edge in concentric relation, the ends of the radially adjacent sections being in alinement, lateral projections carried by the ends of the sections, and clamp bars adapted to engage oppositely with the projections of abutting section ends for support of the sections in rigid relation. 50
- In testimony whereof I affix my signature, 55 in presence of two witnesses.
